United States Patent Office

Des. 202,639
Patented Oct. 26, 1965

202,639

SLED

Stephen A. Holcomb, 1369 N. Las Robles,
Pasadena, Calif.

Filed Aug. 14, 1964, Ser. No. 31,291

Term of patent 14 years

(Cl. D34—15)

Fig. 1

Fig. 2

Fig. 3

FIGURE 1 is a perspective view of my sled, showing my new design;

I claim:

The ornamental design for a sled, substantially as shown.
